DESIGN FOR A POINTER FOR SCALES

Albert A. Schmid, Cicero, Ill., assignor to
Hanson Scale Company, Chicago, Ill., a corpora-
tion of Illinois

Application February 4, 1933. Serial No. 47,107

Term of patent 14 years

To all whom it may concern:

Be it known that I, ALBERT A. SCHMID, a citizen
of the United States, residing at Cicero, in the
county of Cook and State of Illinois, have in-
vented a new, original, and ornamental Design
for a Pointer for Scales, of which the following is
a specification, reference being had to the ac-
companying drawing, forming a part hereof.

In the drawing:

Figure 1 is a face or plan view of a pointer for
scales, showing my new design.

Fig. 2 is an edge view thereof.

I claim:

The ornamental design for a pointer for scales,
as shown.

ALBERT A. SCHMID.
